CONTAINER WITH ENCLOSED TRAP CHAMBER OPERATED BY TIPPING

Norvin E. Smith, Altadena, Calif.

Application October 16, 1945, Serial No. 622,497

2 Claims. (Cl. 222—455)

1

My invention relates to a device for dispensing metered quantities of a substance from a receptacle, and a primary object thereof is the provision of a device of this character which dispenses a metered quantity of the substance whenever the receptacle is partially or completely inverted. The device is particularly adapted for dispensing metered quantities of such powdered or granular materials as coffee, tea, salt, sugar, various condiments, etc., such materials being referred to hereinafter by the general term "granular substance."

Another object of my invention is the provision of a simple and inexpensive dispensing device which may be employed with an existing receptacle, or may readily be incorporated in the receptacle during manufacture thereof.

I contemplate a dispensing device including a conduit member which is secured to the receptacle and is disposed therein adjacent a side wall thereof, the conduit member being provided with a discharge passage which registers with a discharge opening in the upper wall or cover of the receptacle. An object of my invention in this connection is the provision of a conduit member which cooperates with the side wall of the receptacle to provide the discharge passage, thereby simplifying the construction of the dispensing device and reducing the manufacturing cost thereof.

Another object of the invention is to provide such a discharge passage having a downwardly-facing mouth at its lower end which is in open lateral communication with the main chamber of the receptacle through a space between the lower end of the conduit member and the lower wall of the receptacle. Another object is to provide a conduit member which divides the interior of the receptacle into a main chamber and a discharge passage, the latter providing an upper end communicating with a discharge opening in the top of the receptacle, and providing a lower end forming a mouth which openly communicates laterally and openly with the main chamber. In this connection, I have found it undesirable to employ any baffles or barriers at the lower end of the conduit member as they interfere with accurate metering of the granular substance, particularly when the main chamber is practically empty.

Still another object is to provide a conduit member having a lower end which is substantially parallel to the lower wall of the receptacle and is spaced therefrom to provide a metering zone located substantially between the lower end of

2

the conduit member and the lower wall of the receptacle. The granular substance contained in the metering zone is dispensed through the discharge passage and discharge opening whenever the receptacle is partially or completely inverted, the quantity of the substance which is dispensed upon inversion of the receptacle being substantially the quantity contained in the metering zone.

10 A further object of my invention is the provision of a dispensing device of the foregoing general nature wherein the conduit member is secured to the side wall of the receptacle, the conduit member being incorporated in the receptacle during manufacture thereof.

15 An additional object is to provide an alternative form of a dispensing device wherein the conduit member is secured to the upper wall of the receptacle, the upper wall being removable or being part of a removable cover for the receptacle, whereby the assembly comprising the removable upper wall and the conduit member may be employed interchangeably with any one of a plurality of receptacles.

20 Still another object of my invention is the provision of a closure or cap for the discharge opening to provide a seal between the granular substance in the receptacle and the atmosphere, and to prevent contamination of the granular substance when the dispensing device is not in use.

25 The foregoing and various other objects and advantages of my invention may be realized by means of the embodiments shown in the accompanying drawing, which is intended as illustrative only, wherein:

Fig. 1 is a partially sectioned elevational view illustrating a receptacle which incorporates the dispensing device;

30 Fig. 2 is a fragmentary sectional view which is taken as indicated by the broken line interconnecting the arrows 2—2 of Fig. 1;

35 Figs. 3, 4, 5, and 6 are sequence views showing the receptacle in variously inclined positions during inversion; and

40 Fig. 7 is a partially sectioned elevational view illustrating another embodiment of my invention.

45 Referring particularly to Figs. 1 and 2, the dispensing device is incorporated in a receptacle 10 and includes a conduit member 11 which is disposed in, and secured to, some portion of the receptacle. The conduit member 11 is provided with a discharge passage 12 which communicates

50 with the interior or main chamber of the re-

ceptacle 10 and which substantially registers with a discharge opening 13 in the receptacle.

The receptacle 10 is cylindrical in the embodiment shown and includes a circular lower wall 15, a circular upper wall 16, and a cylindrical side wall 17. The lower wall 15 and side wall 17 may be joined in any suitable manner, as by interlocking rolled edges 18 and 19 thereof, respectively. The upper wall 16 may be similarly fixed to the side wall 17 after the receptacle is filled or may be made removable to form a part of a removable cover 21 which may be secured to the side wall 17 by means of a lip or tab 22 which snugly engages the side wall in a conventional manner and which is graspable to remove the cover. The former fixed-wall construction is specifically illustrated in Figs. 1 and 2.

The conduit member 11 is disposed in the receptacle 10 adjacent the side wall 17 and preferably is arcuate to provide a segment 23 of a cylindrical surface which cooperates with the arcuate side wall to provide the discharge passage 12, the discharge passage thus being bounded by a pair of intersecting arcuate or circular walls which are provided, respectively, by the conduit member 11 and the side wall 17, as best shown in Fig. 2. The edges or sides of the conduit member 11 are disposed adjacent the side wall 17 and may be provided with flanges 26 which may engage, and be soldered or otherwise secured to, the side wall 17 to enclose the discharge passage 12.

The discharge opening 13 is formed in the upper wall 16 of the receptacle 10 and, in this embodiment, is preferably bounded by a pair of intersecting circular edges 27 and 28, the edge 27 being substantially concentric with the side wall 17 and the edge 28 being substantially concentric with the cylindrical segment 23 of the conduit member 11. The circular edges 27 and 28 may be deformed tabs which are formed integrally with the upper wall 16 and engage the side wall 17 and cylindrical segment 23, respectively, to provide a convenient means for locating the discharge openings 13 with respect to the discharge passage 12 in a positive manner when installing the cover 21. A removable closure or cap 29 is preferably provided for closing the discharge opening 13, the cap including a projecting portion 31 which may be inserted into the discharge opening into frictional engagement with the tabs 27 and 28. The cap 29 also includes a lip 32 which is adapted to abut the outer surface of the upper wall 16 to limit insertion of the projecting portion 31 into the discharge opening 13 and facilitate removal of the cap.

If the cover 21 is not to be removable, the conduit member 11 may be secured either to the upper wall 16 of the receptacle 10 or to the side wall 17 thereof, or to both. If the cover 21 is removable, the conduit member 11 may be secured to the upper wall 16, the cylindrical segment 23 may be soldered or otherwise secured to the tab 28, and the flanges 26 may be positioned adjacent, but not secured to, the side wall 17. This construction permits use of the cover 21 and the conduit member 11 with any one of a plurality of receptacles, the flanges 26 being disposed sufficiently close to the side wall 17 to prevent excessive leakage of granular substance into the discharge passage 12. For example, when used as a coffee dispensing device, the cover 21, with the conduit member 11 secured thereto, may be installed on a conventional

coffee can to replace the conventional cover thereof.

Regardless of the manner in which the conduit member 11 is secured to the receptacle 10, it is desirable that the lower end of the discharge passage 12 terminate in a mouth 33 which communicates laterally and openly on main chamber 34 of the receptacle through the space between lower end 35 of the conduit member and the lower wall 15 of the receptacle. The mouth 33 preferably faces downwardly when the receptacle is in its normal upright position, and it is a feature of the present invention that this mouth communicate openly with the main chamber 34 in the sense that this communication shall not be through tortuous passages provided by baffles, barriers, cones, and the like, which would tend partially to obstruct free flow of the granular substance to the mouth 33 when the receptacle is tipped in such direction that the mouth 33 is adjacent the lowermost corner thereof.

It is also desirable that the lower end 35 of the conduit member 11 be spaced from the lower wall 15 of the receptacle to provide a space through which the mouth 33 openly communicates with the main chamber 34, and that this lower end 35 be substantially parallel to the lower wall 15. In effect, such a structure provides a metering zone 36 which is located substantially between the lower end 35 and the lower wall 15. The metering zone 36 is bounded by the lower end 35 of the conduit member 11, the side wall 17 of the receptacle 10, the lower wall 15 of the receptacle, and an assumed extension of the cylindrical segment 23 of the conduit member, as indicated by the broken lines 37. The granular substance contained in the metering zone 36 is dispensed through the discharge passage 12 and discharge opening 13 whenever the receptacle 10 is partially or completely inverted, the quantity dispensed being substantially the quantity contained in the metering zone if the receptacle is inverted at a reasonably rapid rate.

Whenever a metered quantity of the granular substance in the receptacle 10 is desired, the receptacle is rotated in the direction indicated by the arrows 39. Successive positions of the receptacle 10 are shown sequentially in Figs. 1, 3, 4, 5, and 6, the changing position of the surface of the granular substance in the receptacle being indicated by the numeral 40. If the receptacle 10 is rotated relatively slowly, a small excess quantity of the granular substance may flow from the metering zone 36 into the discharge passage 12 before the receptacle is inverted, the excess quantity being indicated by the numeral 41 in Figs. 3 and 4 and being replaced by a corresponding quantity which flows into the metering zone from the interior of the receptacle. However, if the receptacle 10 is rotated at any reasonably rapid rate, the excess quantity 41 will be negligible, particularly if the granular substance flows readily. As shown in Fig. 5, the changing surface 40 of the granular substance in the receptacle 10 soon coincides with the lower edge of the conduit member 11 when the receptacle assumes an inverted position to prevent further discharge. The quantity of the granular substance in the metering zone 36, plus the small excess quantity 41, are dispensed through the discharge passage 12 and the discharge opening 13 as indicated by the numeral 42 in Fig. 5. Experiments have shown that, if the receptacle 10 is inverted reasonably

rapidly, the dispensed quantity 12 is substan-

tially the quantity contained in the metering zone 36, the excess quantity 41 being negligible, and that the metered amount is substantially independent of the degree to which the main chamber of the receptacle is filled. Thus, the device dispenses metered quantities of the granular substance quite accurately, the metering action being substantially independent of the quantity of the granular substance in the receptacle 10.

A coffee-dispensing device, designed to dispense about a heaping tablespoonful of coffee sufficient for making one cup of coffee, can be formed with the following exemplary dimensions. With the usual metal coffee can of a diameter of about 4 $\frac{1}{8}$ " and a height of about 3 $\frac{3}{8}$ ", the wider dimension of the discharge passage may be about 1 $\frac{1}{4}$ ", the narrower dimension being about $\frac{3}{4}$ " and the distance from the lower wall 15 and the lower end 35 of the conduit member being about $\frac{3}{4}$ ", more or less, as determined by the exact amount to be dispensed.

The embodiment of my invention shown in Fig. 7 illustrates a modified conventional coffee can 45 which incorporates the dispensing device, the conduit member 11 being disposed in the coffee can and being suitably secured thereto to provide the discharge passage 12, as previously described. The coffee can 45 is provided with a fixed false upper wall 46 which corresponds to the upper wall 16 of the embodiment shown in Fig. 1, the upper wall 46 being provided with the discharge opening 13 therein and being fixed in place after the receptacle has been filled. The coffee can 45 includes the conventional removable cover, which is indicated by the numeral 47. After removing the cover 47, the coffee can 45 may be upturned, with the conduit member downward, to dispense a metered quantity of coffee in the manner previously described.

The conduit member 11 may be employed with existing receptacles or may be incorporated therein during manufacture thereof to provide a simple and inexpensive dispensing device. Since the conduit member 11 cooperates with the side wall 17 of the receptacle 10 to provide the discharge passage 12, the construction of the dispensing device is simplified appreciably. The conduit member 11 may be secured to the cover 21 of the receptacle 10, whereby the dispensing device may be used interchangeably with any of a plurality of receptacles, or the conduit member may be secured to the side wall 17 of the receptacle, if desired.

Although I have illustrated and described various embodiments of my invention, I do not intend to be limited to the specific disclosures contained herein since various changes, modifications, and substitutions may be incorporated in the embodiments disclosed without departing from the spirit of the invention, and I hereby reserve the right to all such changes, modifications, and substitutions as properly come within the scope of the appended claims.

I claim as my invention:

1. In a device for dispensing a metered quantity of a granular substance, the combination of:

a receptacle for the substance, said receptacle having a lower wall and a side wall extending upwardly from said lower wall; a removable cover for said receptacle and engageable with said side wall thereof, said cover having a discharge opening therein, said cover being imperforate except for said discharge opening; and means carried by said cover for dividing the interior of said receptacle into a main chamber and a discharge passage when said cover is on said receptacle in engagement with said side wall thereof, said means comprising a conduit member fixed to said cover, said conduit member being disposed in said receptacle adjacent said side wall thereof and cooperating with said side wall to define said discharge passage when said cover is on said receptacle, said discharge opening communicating with said discharge passage when said cover is on said receptacle, and said conduit member having a lower depending arcuate edge which is spaced from said lower wall of said receptacle by said cover when said cover is on said receptacle to provide an arcuate throat between said depending edge and said lower wall of said receptacle.

2. In a metering device for use with a receptacle having a lower wall and a side wall, the combination of: a cover for the receptacle, said cover having a graspable portion and a portion engageable with said side wall of said receptacle, said cover having a discharge opening therein but being otherwise imperforate; and means carried by said cover adjacent said discharge opening for dividing the interior of the receptacle into a main chamber and a discharge passage when said cover is on the receptacle in engagement with the side wall thereof, said means comprising a conduit member fixed to said cover adjacent said discharge opening and having two longitudinal edges respectively engageable with angularly-displaced zones of said inner surface of the side wall of the receptacle, said conduit member cooperating with the side wall of the receptacle when said cover is on the receptacle to define said discharge passage, said discharge opening registering with said discharge passage, said conduit member being shorter than said side wall and having a depending edge extending between said longitudinal edges and arching between said angularly-displaced zones when said cover is on said receptacle, said depending edge being spaced from the lower wall of said receptacle by said cover when said cover is on the receptacle.
